UNITED STATES PATENT OFFICE

120,241

DESIGN FOR A CORNER PIECE FOR BURIAL CASKETS

Stephen Junkunc, Jr., Oak Park, Ill., assignor to Stephen Junkunc, Sr., Oak Park, Ill.

Application November 24, 1939, Serial No. 88,452

Term of patent 14 years

To all whom it may concern:

Be it known that I, Stephen Junkunc, Jr., a citizen of the United States, residing in Oak Park, in the county of Cook, State of Illinois, have invented a new, original, and ornamental Design for Corner Pieces for Burial Caskets, of which the following is a specification, reference being had to the accompanying drawing, forming part thereof.

Figure 1 of the drawing is a perspective view of a corner piece for burial caskets embodying my design; Fig. 2 is a front view of the corner piece; and Fig. 3 is an end view of the corner piece looking at the end which is at the top in the other views.

I claim:

The ornamental design for a corner piece for burial caskets, as shown.

STEPHEN JUNKUNC, JR.
